MECHANICAL PENCIL

Christ Andonov, Gary, Ind.

Application June 11, 1952, Serial No. 292,886

2 Claims. (Cl. 120—143)

This invention relates to pencils of the propell-repel type wherein a graphic writing material is caused to advance or retract upon the operation of a hand knob.

More particularly, this invention contemplates the provision of a multiple-lead pencil in which four different colors of writing material are available for use in a single pencil housing. There are at present several commercial embodiments of such a plural-lead pencil available on the market. However, these are generally quite expensive and suffer the disadvantage that the lead is propelled in an axis not parallel with the axis of the pencil which causes some discomfort and a tendency for the pencil to pivot in the writer's hand as the lead becomes worn. A further limitation generally present in such plural-lead pencils is that the leads are ejected by a manual sliding type plunger which does not allow a generally infinite adjustment of the lead length. Yet another disadvantage often found in the present commercial embodiments is that some reciprocating apparatus operated by the writer's fingernail is utilized to place the desired color of writing material in position for writing. The latter is particularly undesirable since women tend to break their fingernails operating the pencil, while men often find their nails too short for easy operation of the mechanism.

Each of the above noted deficiencies of the prior art devices is corrected in the construction of the instant invention, which provides a rather simple and inexpensive automatic pencil which may be completely controlled through the manipulation of a single knob at the upper end of the instrument.

It is an object of this invention, therefore, to provide a novel pencil which allows the use of a plurality of different colors of lead.

A further object of this invention is to provide a multi-colored lead pencil that requires no manipulation other than that available from the thumb and forefinger.

Yet another object of this invention is to provide a multi-lead pencil which permits the writing lead to be expelled parallel to the axis of the pencil.

Still a further object of this invention is the provision of a multi-lead pencil wherein the writing material may be expelled and retracted by the mere rotation of a control knob conveniently placed at the upper end of the instrument.

A further feature of the present invention is the provision of a multi-lead writing pencil which comprises an indexing arrangement wherein the colors, or writing leads, not in use are rendered completely inoperative and are fully enclosed in a position wherein no soiling or other injury may occur to the writer or his clothes.

Still a further feature of this invention is the provision of a plural lead pencil having an offset writing tip which automatically maintains the pencil in the most comfortable position for writing and prevents any rotation of the pencil in the writer's hand.

A further object of the present invention is the provision of an extremely durable and ruggedly constructed

2

plural lead writing instrument in which the various component parts are not dependent upon ratchets or other detent arrangements generally found unsatisfactory from the point of view of durability.

5 Other objects and features of this invention will more fully appear from the following detailed description taken in connection with the accompanying drawings which illustrate a single embodiment thereof.

On the drawings:

10 Figure 1 is a side view of the pencil of my invention in its assembled condition;

Figure 2 is an expanded cross-sectional view of my pencil as shown in Figure 1, and taken along the lines II—II of Figure 1;

15 Figure 3 is a cross-sectional view of the pencil shown in Figure 1 and is identical to the construction shown in Figure 2 except that the working parts are in the color-changing position;

20 Figure 4 is a cross-sectional view taken along the lines IV—IV of Figure 2, and discloses the construction utilized in the propelling and repelling of the writing leads; and

25 Figure 5 is a cross-sectional view taken along the lines V—V of Figure 3, and shows the general arrangement of the clutching mechanism utilized for operation of the desired lead.

As shown on the drawings:

As shown in Figure 1, the pencil of my invention comprises generally a pencil having a housing portion 1, a generally conical point 2 and an operating knob 3. A graphic writing lead or other suitable cylindrical writing material is propelled, as indicated at 4, from the tip 2.

As may be more clearly seen in Figure 2, the tip 2 is offset from the longitudinal axis of the pencil body 35 as a whole in order that my novel indexing mechanism generally discussed below may be utilized. As further seen from this view the housing portion 1 interconnects with the tip 2. This connection may be threaded, or any other type of suitable rigid connection such as press fit, glue, or soldering.

45 An indexing head or member 5 is rotatably mounted within the housing barrel 1 and comprises a cylindrical member having a plurality of axial bores 6. It is to be understood, of course, that any number of such bores could be utilized, and that the number arbitrarily chosen as 4 in the present application is merely indicative of the general arrangement. The indexing head is rigidly secured to a pin 7 by means of an embedded head 8 or other permanent means. The pin 7 is in turn passed through a bearing 9 which is semi-permanently fixed to the tip 2, preferably by means of a very tight press fit. A head 10 is formed on the right hand end of pin 7 and a resilient spring 11 is positioned between this head and the bearing 9.

55 At the upper end of the indexing head member 5 an axial bore 12 is provided. Within this bore 12 a clutching element 13 is fixedly placed. As may be seen from the showing in Figure 5, this clutching element has a generally cylindrical exterior surface and a polygonal 60 interior surface. While the clutching member 13 is disclosed as having a cylindrical exterior surface it is contemplated that in heavy duty installations the exterior surface could be serrated to provide a more positive grip between the surface of the member 13 and the bore of the indexing head 5.

The cap 3 is provided with a pin 14 having a round head 15 thereon. A reduced diameter portion indicated at 16 is of a polygonal cross-section which conforms to the cross-section of the interior surface of the clutching 70 member 13 to provide a rotary drive connection between the cap 3 and the indexing head member 5 when the portions 16 and 13 are engaged. A spring 17 is positioned

between the head 15 and the clutch member 13 and tends to maintain the head 15 at the lower disengaged position in the bore 12. In the assembly of the device the stem 14 is placed in the bore with the head 15 at the lower portion of the bore 12, the spring 17 and member 13 are inserted around the stem 14 and the clutching member 13 is then pressed into the bore 12 in a tight fit. This clutch member may be soldered or glued, depending upon the materials utilized in the pencil, or may be otherwise fixedly secured as above suggested. The cap 3 is then forced upon the end of the stem 14 in a secure position.

Into each of the bores 6 a commercially standard pencil propel-repel mechanism is inserted. These mechanisms are maintained in position in the tubes by means of the roughened or knurled surfaces 18. Each of the propel-repel mechanisms comprises a lead carrying tube 19 surrounded by a helical strip 20. Each of the tubes 19 is slit from end to end inside of the helical strip and a generally well known lead carrying member having projections 21 is reciprocably mounted within the tube. The projections 21 cooperate with the edges of the strips 20 to reciprocate the lead upon rotation of the tube 19 with respect to the helical strip 20. The helical strip 20 is fixedly secured to the roughened member 18 and is thereby fixed securely to the indexing head 5.

In order to produce relative rotation between the tube 19 and the helical strip 20 the tube is squared at its upper end as indicated at 22 and as clearly indicated in Figure 5. The squared clutch portion 22 cooperates with an actuating means in the form of a gear 23 which is supported for rotation about its own axis by a yoke support fixed to the housing 1 as indicated at 24 and as clearly shown in Figure 4. The gear 23 has an annular groove 25 formed in its exterior surface, and teeth 26 are machined into the root of the groove. The teeth 26 cooperate with a ring gear 27 which is integral with or firmly affixed to the cap 3. The sides of the groove 25 in the gear member 23 cooperate with the sides of the ring gear 27 to maintain the gear 23 in a fixed axial position relative to the cap 3.

At the tip end of the pencil the tubes 19 are arranged to align with depression 29 in the tip 2. This arrangement positively retains the indexing head 5 in its adjusted angular position with one of the tubes 19 facing the lead aperture 30.

The operation of the invention may be clearly seen from a consideration of Figures 2 and 3. In Figure 2, the pencil is shown in its operative condition with the lead 4 from one of the tubes 19 projected into a position of use. In this position it will be noted that the gear 23 is in engagement with the square clutch portion 22 of the tube 19, thereby connecting the tube for simultaneous rotative movement. Since the gear 23 is maintained in axial alignment with the tube 19, which is aligned with the lead aperture 30 by means of the yoke 24, rotation of the cap 3 will cause the gear 23 to rotate in the same direction as the cap. This rotation will cause relative movement between the tube 19 and the fixed spiral strip 20 thereby causing reciprocation of the lead propelling members 21 which in turn causes the lead 4 to be expelled through the aperture a bore 30.

It is noted that in the position shown in Figure 2 the four tubes 19 are maintained in the recesses 29 by spring 11, thereby preventing rotation between the indexing head 5 and the tip 2. When it is desired to change colors or different leads it is necessary to rotate the indexing head 5 until a different tube 19 is in alignment with the lead aperture 30. This is done by pulling the knob 3 upwardly and then rotating it 90° until a new tube 19 is in axial alignment with the opening 30. As is shown in Figure 3 when the cap 3 is moved upwardly the squared portion 22 becomes disengaged from the gear member 23 and the tubes 19 become disengaged from the recesses 29 against the biasing means 11.

With the parts in this position, the cap 3 may be ro-

tated in either direction. Since the square chuck portion 16 is now located within the polygonal cavity in the chuck member 13, the rotational movement given the cap 3 will be imparted to the chuck member 13 and from thence to the indexing head 5. Upon arrival of the desired lead carrying tube 19 to a position in alignment with the lead aperture 30, the cap is released. When released, the spring 11 forces the tubes 19 into the recesses 29 and the spring 17 forces the cap 3 downwardly so that the gear member 23 is in drive relation with the square clutch portion 22 of the tube 19 which is in alignment with the lead dispensing aperture 30. With the parts in this position rotation of the cap 3 will, as above stated, cause the lead to be propelled from the tube 19 into the aperture 30 and outwardly into operative position. It is, of course noted that in operation it is necessary to retract the individual leads 4 back into the tubes 19 in order to rotate the indexing head 5 without damage to the leads.

From the above description it will be readily apparent that the present invention provides a substantially improved multiple-color writing instrument utilizing a simple, extremely durable and very compact mechanism which requires no difficult manipulation with the fingernails in its operation.

25 It will be understood that modifications and variations may be effected without departing from the scope of the novel concepts of the present invention.

I claim as my invention:

1. In combination in a multilead pencil, a tubular housing, an offset tip fixedly secured to said housing, an index member coaxially rotatably mounted within said housing, said index member having a plurality of bores peripherally spaced about the rotational axis of said index member at the same radial distance from the central axis of said housing, said tip having an axial bore positioned the same distance from the said central axis as the said plurality of bores, a lead propel-repel mechanism in each of said bores and having a clutch member and operable upon rotation of said clutch member to reciprocate a lead secured therein, a cap reciprocably and rotatably carried by said housing, actuating means in said cap reciprocable therewith and rotatable relative thereto for operative engagement with the clutch member of a selected one of said mechanisms in alignment with the bore in said tip when said cap is reciprocated toward said tip into a first position, means locking said index member against rotation relative to said housing when said cap is in said first position, means on said housing for cooperation with said actuating means to maintain said actuating means in axial alignment with the bore of said tip, cooperating gear teeth on the external periphery of said actuating means and the internal periphery of said cap whereby rotation of said cap will rotate said actuating means to rotate said clutch member when said cap is in said first position and said actuating means is in engagement with said clutch member, and means connecting said cap to said index member for rotation thereof to change the selected mechanism in alignment with the bore of said tip, said last named means being operable only when said cap is moved away from said tip into a second position in which actuating means is out of engagement with said clutch member.

2. In combination in a multilead pencil, a tubular housing, an offset tip fixedly secured to said housing, an index member coaxially rotatably mounted within said housing, said index member having a plurality of bores peripherally spaced about the rotational axis of said index member at the same radial distance from the central axis of said housing, said tip having an axial bore positioned the same distance from the said central axis as the said plurality of bores, a lead propel-repel mechanism in each of said bores and having a clutch member and operable upon rotation of said clutch member to reciprocate a lead secured therein, a cap reciprocably and rotatably carried by said housing, actuating means in said cap re-

ciprocable therewith and rotatable relative thereto for operative engagement with the clutch member of a selected one of said mechanisms in alignment with the bore in said tip when said cap is reciprocated toward said tip into a first position, means locking said index member against rotation relative to said housing when said cap is in said first position, means connecting said cap to said locking means for unlocking said index member when said cap is reciprocated away from said tip into a second position in which said actuating means is out of engagement with said one mechanism, gear means on the periphery of said actuating means for cooperation with gear means on the internal surface of said cap rotating said actuating means upon rotation of said cap to thereby rotate said clutch member when said cap is in said first position, and means connecting said cap to said index member for rotation thereof to change the selected mech-

anism in alignment with the bore of said tip, said last named means being operable only when said tip is in said second position in which said locking means is disconnected and in which said actuating means is out of engagement with said clutch member.
